UNITED STATES PATENT OFFICE.

SMITH W. CLARK, OF DELANCO, NEW JERSEY.

FLOWER-POT MACHINE.

SPECIFICATION forming part of Letters Patent No. 511,587, dated December 26, 1893.

Application filed July 29, 1892. Serial No. 441,617. (No model.)

To all whom it may concern:

Be it known that I, SMITH W. CLARK, a citizen of the United States, residing at Delanco, in the county of Burlington and State of New Jersey, have invented certain new and useful Improvements in Machines for Making Flower-Pots and Pottery-Ware; and I do hereby declare the following to be a full, clear, and exact description of the invention, such as will enable others skilled in the art to which it appertains to make and use the same.

My invention has relation to machines for making flowerpots and analogous articles; and it has for its principal object the assembling of a number of jiggers for simultaneous operation in a single machine; automatic delivery of the finished pots, and automatic feed of clay to the different molds for the different jiggers, whereby a separate attendant for each jigger as heretofore required is dispensed with, the output very largely increased, and its cost very materially reduced.

My invention accordingly consists of the combinations, constructions, and arrangements of parts as hereinafter described in the specification and pointed out in the claims.

Reference is had to the accompanying drawings wherein Figure 1, is a side elevation, partly in section, of a machine embodying my improvements, the automatic feeding devices for the molds not being shown. Fig. 2, is an elevation partly broken away, and partly in section, of the delivery end of the machine. Fig. 3, is an elevation of the mechanism for engaging the mold support to intermittently rotate it. Fig. 4 is a front view of the disk with the recesses or notches in its periphery, located on the shaft for the mold support, and forming part of said engaging

mechanism. Fig. 5, is a like view of the other part of said mechanism carrying the movable pin for engaging with the recesses or notches in said disk. Fig. 6, is a section of the mechanism shown in Fig. 5, through the line of the sliding pin. Fig. 7, is an end elevation of the same and bracket support showing a cam finger for releasing said pin from said notches at the completion of the intermittent rotation of the mold supporting frame. Fig. 8, is a perspective of one form of pallet supporting frame for receiving the pots and conveying them to the delivery

apron or device. Fig. 9, is a plan of the automatic feeding device for the molds illustrating a relative location of the pug mill, 55 feeding devices and the molds. Fig. 10, is a plan drawn to enlarged scale of part of the feeding devices illustrating more plainly the manner of successively bringing into position the supply of clay for injection into successive 60 molds, and Figs. 11 and 12 are sections on the lines 1-1 and 2-2 respectively in Fig. 10.

A represents a housing or frame of the machine which may be of any suitable configuration and construction.

B represents the plunger frame which is shown vertically located and having an up-and-down movement. In this frame are mounted a number of jiggers, b, having separate spindles, b', upon each of which is suitably secured a beveled wheel, b², meshing with like wheels b³ upon the driving shaft b⁴, 70 horizontally mounted upon frame B in suitable bearings, and moving with said frame.

Upon shaft b⁴, is mounted a pulley b⁵ having a belt connection b⁶, with a suitably-located power shaft not shown in the drawings. The relative position of the shaft b⁴, and said power shaft is preferably such that as the frame B descends, and the jiggers b enter the 80 molds to be hereinafter described, the belt connection b⁶ for pulley b⁵ will be taut, thereby revolving shaft b⁴ in order to rotate the jiggers as they descend into the molds. Such relative arrangement admits of the jiggers 85 rotating only at such time as it is necessary for them to perform their work, they at all other times being idle or not rotating owing to the slack of the belt connection b⁶, as the jiggers b ascend from and descend to the 90 molds.

Any suitable mechanism may be employed for vertically reciprocating frame B. I prefer a form of the same which will give the frame a slow descending motion and a quick 95 return. In the drawings a form of mechanism is shown comprising a shaft C, suitably mounted in frame A having fixed thereon spur-wheels c c which mesh with racks c' secured to frame B and also a large and small pulley c² c³ respectively running loose on shaft C, and adapted for alternate engagement with the clutch box c⁴, having an operating lever c⁵. The clutch box c⁴ is alternately engaged

with the wheels c^2 c^3 by the frame B at the end of its descending and ascending movements through the medium of a bell-crank lever c^6 , and lever c^7 respectively located at 5 the terminal points and in the path of movement of the frame B. The levers c^6 c^7 are suitably mounted in the frame A and as shown in the drawings occupy positions relatively to the frame B. See more plainly Fig. 2. The 10 wheel c^2 on shaft C has a straight belt connection c^8 and the wheel c^3 has a cross belt connection c^9 with a suitable power shaft not shown in the drawings whereby when the clutch box c^4 is in engagement with the wheel c^2 the shaft C is rotated in one direction to move the frame B downwardly and when the clutch c^4 is in engagement with the wheel c^3 shaft C is reversedly rotated to cause a quick 15 return of frame B.

20 To vary the length of movement of the frame B in making different heights or sizes of pots, the frame B is provided with any suitable form of adjustable striker arms D, D', as shown more plainly in Fig. 2, in which 25 case the upper striker arm D' has the greater degree of adjustment for the different heights of pots as the lower striker arm is adjusted only to compensate for the different thicknesses of the bottoms of the different sizes of 30 pots.

35 E represents the intermittently rotating mold support, having on opposite surfaces and on opposite sides of its shaft e two sets of molds F, F', as shown more plainly in Fig. 1, so that when rotated one set of molds is brought into line with the jiggers and the other set is moved or turned down to the under side of the frame E to admit of the ejection therefrom of the pots previously formed 40 therein. The mold supporting frame E may be of any suitable construction and its shaft e journaled in the frame A as desired. The molds F F' may be of any suitable construction and be integral with or separate from the frame E. I prefer the latter as they may 45 be moved from the frame E and replaced by others of different size in the making of different size of pots, in which case the jiggers b must be changed accordingly. In the 50 drawings the molds F F' are shown separate from and attached to frame E, by means of flanges f on the molds, and bolts f' the heads of which enter suitable grooves e' in the support E. Each mold is provided with any suitable ejector f² one end of which forms either a part or the whole of the bottom of the mold as is usual or as desired. Each ejector has a head f³ and a reacting spring f⁴ as shown.

55 Any suitable means may be provided for 60 intermittently rotating the frame E, and for actuating the ejector f². In the drawings see Figs. 3 to 7 inclusive the form of mechanism for actuating the support E comprises a disk G, mounted at one end upon the shaft e of frame E in the periphery of which disk are two oppositely located notches or recesses g. Parallel with disk G, and mounted upon a

separate shaft h aligning with shaft e is another disk H. Upon the latter is suitably mounted a movable or sliding pin h' which is 70 in the plane of the disk G. The pin h' slides in suitable bearings in the disk H, and has a retracting spring h² the tendency of which is to draw or move the pin h' toward the shaft h. Projecting from the pin h' or the 75 frame to which it is attached, and passing through a radial slot h³ in disk H to and beyond the front face thereof, is a lug h⁴. The shaft h, is mounted in a suitable bracket h⁵, and is provided with a driving pulley h⁶, 80 to the bracket h⁵ and in line with a recess g in disk G located at the terminal of its intermittent motion, is secured an incline or cam finger h⁷, the bottom of said incline or cam being flush with or slightly projecting beyond 85 the periphery of the disk G at said recess, as more plainly shown in Fig. 7. From this construction it will be noted that the pin h' when the disk H and shaft h are revolved, rides on the periphery of the disk G until it arrives 90 at one of the recesses g, whereupon the retracting spring for the pin h' moves it into said recess to couple the disks G and H which then move together to rotate the mold supporting frame E one half of a revolution. Before completing this half revolution the lug h⁴ of pin h' meets and rides upon the cam or incline h⁷ which acts to push the pin h' out of its engaging recess g in disk G at the time 95 said half revolution is completed, and the disk H continues revolving with the pin h' riding on the periphery of the disk G, until said pin meets another recess g to engage therewith and intermittently rotate the mold supporting frame E as above described. This intermittent motion of the mold supporting frame E alternately brings one set of molds F, into 100 the line of the jiggers b in which location the supply of clay for each mold of the set F is inserted or conducted into said molds as 105 shown in Fig. 1, and the other set of molds F' is turned top-side-down below the frame E in which position the pots are ejected from the molds F' on to pallet boards for delivery from the machine. In this position the frame B 110 with the jiggers descends and said frame carrying with it a finger or toe I strikes the heads f³ of the ejectors f² which push the pots from the molds F' on to the pallet board k, which is then in position upon the pallet board support or table below said molds F' as indicated by dotted lines x Fig. 1. The pallet board supporting table K, then descends until it reaches a traveling apron k' which engages 115 and transfers the pallet with the pots therein to the place of delivery or stacking.

120 Any suitable pallet board support K and actuating mechanism therefor may be used. In the drawings a form of support comprising a frame with an open top having end ledges k² and cross bar k³ at its rear top edge which frame is suspended or pivoted to one end of arms k⁴ the other ends of which are rigidly secured to a shaft k⁵ is shown. Secured to

shaft h^5 is another arm h^6 the free end of which is in connection with an eccentric h^7 on shaft h whereby when shaft h is revolved the pallet supporting frame K is raised to the molds F or F' to receive the pots and then moved downwardly to deliver the same to the transferring apron h' . Such ascent and descent is provided for in order to move the pallet supporting frame K out of the way of the mold supporting frame E as it is rotated.

The supply of clay for each mold may be fed into it by hand but I prefer to effect such result automatically and any suitable mechanism may be employed for such purpose, a form of which is indicated in Figs. 9 to 11 inclusive. L represents any suitable form of pug mill having a cutter l for dividing the clay into the proper lumps or supply for the pot to be formed and a transferring apron l' for conducting these supplies to the chutes m leading to the molds upon the support E. The chutes m are located at right angles to the transferring apron l' . In line with the chutes and extending across the apron are clay supply stopping and pushing rods m' , the part m^2 of said rods being used for stopping the movement of the clay with the apron so as to hold it in front of a chute into which it is to be pushed and the part m^3 of said rods being the pusher device for transferring the clay from the apron to the chute. These rods m' , at one end m^4 are hinged or pivoted to a swinging frame m^5 , so that all of the said rods except the last one or that farthest away from the plug mill are free to rise and fall on their hinged connections with the frame m^5 , and the latter when moved, impart to the rods a longitudinal movement. The rods m' also have a lateral movement and to effect this they may be made into sections and jointed or they may be pivoted to their sleeve supports on the frame m^5 . The rods m' near their outer ends m^7 have an arm extension with roller m^8 . The ends m^7 of rods m' project beyond the apron l' and all of them except the last one normally rest upon the top of the incline n running parallel with the apron l' and having formed therein, in line with or adjacent to the chutes m , inclined slots n' said incline terminating in a bottom horizontal ledge n^2 . A slot n' in the incline n is provided for each limiting and pushing bar m' except the last one in order that each successive bar m' may be automatically actuated to come into position and hold a supply of clay in position on the apron l' opposite the respective chute m , into which it is to be pushed. The incline bar n opposite the last pushing and limiting bar m' , has its incline cut away and secured to its ledge n^2 is a short vertically arranged incline n^3 , for moving it laterally. This bar is never raised as it is the last bar of the series and does not have to be out of the way of any clay supply for the chutes ahead of it, while all the other bars m' must be raised and lowered successively to admit bringing the clay supply to

them. The bars m' are connected to each other by links n^4 having loose play therein, equal to the distance of lateral movement of the bars. Normally the bars are in position at the top of the incline n , except the last bar m' , the end m^7 of which is away from but in line with the bottom of incline n as shown in Fig. 9, and hence said bar rests in position but slightly above the top of the apron, while all the other bars are elevated a distance therefrom sufficient to admit the clay supplies passing beneath them as they move along the apron. The first clay supply transferred to the rapidly traveling apron l' is carried with it until it meets the last bar m' , against which it impinges and moves said bar laterally until its end m^7 strikes the bottom of the incline n^3 , by means of which, said bar is held and in turn holds said clay supply in position in front of the pushing lug m^8 . As said last bar moves laterally its link connection n^4 with the next succeeding bar causes it to move into its slot n' on the incline n through which it drops into position close to the apron l' for holding the succeeding clay supply, and said bar in turn as it drops and moves laterally brings the next succeeding bar into position close to the apron through the medium of its link n^4 and so on until all the bars m' have dropped into position. The swinging frame m^5 is then actuated to simultaneously move all the bars m' lengthwise in the direction of the chutes for pushing their respective clay supplies into the chutes. As the bars m' move lengthwise their roller arms m^8 ride up the incline n and are thereby raised above the apron, to one side of their slots n' in said incline, so as to be in normal position for the feeding of the next clay supply. The last bar m' instead of being raised is moved laterally by its incline n^3 . The swinging frame is then reversely moved to its normal position, all the bars m' moving therewith but remaining in the position last described so as to be normal for successive action. Each lump of clay supply therefore moving with the apron l' meets and laterally moves the bar m' against which it impinges and the lateral movement of said bar simultaneously drops the next succeeding bar close to the apron for a like impingement and movement by the next succeeding lump of clay supply, and so on until all the bars m' have been dropped close to the apron with the clay supplies in position for being transferred to the chutes by the movement of the frame m^5 , the bars as they are moved by the swinging frame to push the clay into the chutes being automatically actuated by the inclines n and n^3 to return to their normal positions.

From the foregoing it will be noted that when the mold support E, is in its normal position as shown in Fig. 1 after being rotated the jiggers b or the frame B is at the end of its ascent and the pallet carrying frame K, is at the end of its descending movement, the traveling apron h' having engaged with said

pallet and is transferring it to the delivery or stacking place; that when the clay supplies are fed into the mold the frame B descends, the jiggers b enter the molds the presser-foot 5 I actuates ejectors f² for pushing the pots out of the molds adjacent to the pallet carrying frame K which meanwhile has ascended to be in position for receiving the ejected pots.

If desired the pallets may be fed to the frame K just before it reaches the terminal of its ascending movement. To effect this the pallets are placed upon a fixed chute p suitably located in the frame A, and are pushed onto the frame K when ascending, the end ledges k^2 and the rear cross bar k^3 at its top guiding the pallets into position thereon. The pulley h^6 on shaft h has a belt connection with the power driving shaft and is timed to make one complete revolution for every to 15 and fro movement of the jigger carrying frame B, so that while the pin, h' of disk H, after being uncoupled from the disk G and is riding around on the lower half of its periphery, ample time is afforded for the jiggers to 20 25 form the pots in the molds and ascend, and also for the pallet carrying frame K, when said pin couples with the disk G to intermittently rotate it. To prevent the pressure of the jiggers in the molds tilting the mold supporting frame E during the jigger operation a suitable lock p' engaging with said frame is provided as shown in Fig. 1, said lock being hinged to the frame A and having a retracting spring in order that the frame E 30 35 when rotated may push the lock aside in passing the same, its retracting spring causing the lock to re-engage itself with the frame at the completion of its rotation. The apron k' may remove the pallet with the pots thereon 40 45 45 from the supporting frame K by frictional contact between the apron and the bottom of the pallet, or if desired suitable lugs may be attached to the apron for engaging with the edge of the pallet, in which case suitable openings k^{10} will be formed in the cross bar k^3 of the frame K, for the lugs to pass through to effect such engagement.

From the foregoing it will be noted that the cut-supplies of clay from the pug-mill 50 are first positioned on the apron *l'* and then advanced or pushed simultaneously into the respective chutes *m* from which they drop into a series of molds *F* then in their receiving position or on the top side of the mold 55 supporting frame *E*. The frame *B* with the rotating jiggers then descends to form the pot in the mold; said frame *E* remaining stationary until the pots are formed at which time it makes a half revolution; the frame *B* and 60 its jiggers having previously ascended to be out of the way of the rotating mold-frame *E*. As the latter rotates to carry the finished pots in the molds to the pallet supporting-frame *K*, a pallet is fed thereon by hand, gravity or 65 other wise as desired so as to be in position for receiving the pots as they are ejected from the molds by bar *f* striking the ejectors

f³ on the next descent of the frame B and the jiggers. Hence every time the mold supporting frame is rotated one series of empty molds are brought into position to be supplied with clay and the pots are formed therein, and another series of molds with pots formed therein are carried to a discharging position, the forming of the pots and the discharging *75* of the same being accomplished while the frame E is at rest.

I do not confine myself to the relative arrangements of the essentials of my invention nor to the construction and arrangement of the actuating devices for said essentials as shown, as the same may be variously changed without departing from the spirit of the invention which has for its fundamental idea the assembling of a number of molds and jiggers in the same machine, automatically ejecting the finished pots from the molds and transferring them to the delivery or stacking station and finally automatically feeding the clay supplies to the molds. 80 85 90

It is evident that if desired the automatic feeding device, the intermittently rotating support and pallet carrying frame may be applied to single as well as to multiple jigger machines.

What I claim is—

1. In a flower pot machine the combination of vertically moving and rotating jiggers, of a mold supporting frame mounted on a horizontally located shaft and having molds 100 on its opposite sides, ejectors in said molds, and actuating mechanism for automatically imparting an intermittent rotary motion to said mold supporting frame, substantially as set forth.

2. In a flower pot machine a mold supporting frame mounted on a horizontally located shaft, molds on the upper and lower side of said supporting frame, ejectors for all the molds and actuating mechanism in engagement with said shaft for automatically imparting an intermittent rotation to the mold supporting frame and causing it to dwell between alternate rotations for forming the pots in the molds on the upper side of the supporting frame substantially as set forth

3. The combination in a flower pot machine of a mold-supporting frame mounted upon a horizontal shaft, molds on opposite sides of said frame, ejectors for the molds, and actuating mechanism for automatically imparting an intermittent rotary motion to the mold frame, substantially as set forth. 120

4. The combination of a rotating jigger and its actuating mechanism, a mold supporting-frame separate from the jigger, molds on opposite sides of said frame, an ejector in each mold, and actuating mechanism for said ejectors and for the mold supporting-frame, substantially as set forth. 125

5. The combination of a rotating jigger a
mold supporting frame separate from the jigger,
a pallet carrying-frame, and actuating
devices, substantially as described. 130

6. The combination of a vertically sliding jigger frame mechanism secured to said frame for rotating said jiggers, a mold supporting frame having molds with the ejecting devices on opposite sides of the frame, means for intermittently rotating said frame, a pallet carrying frame and actuating devices for the jigger, mold ejector and pallet carrying frame substantially as set forth. 35
- 10 7. The combination of a vertically sliding jigger frame having a quicker return than descent and intermittently rotating mold supporting frame having molds on opposite sides, ejectors for said molds, a movable pallet supporting frame and actuating devices substantially as set forth. 40
- 15 8. In a pottery machine, a mold which receives the clay and in which the clay is formed or jiggled with the open top of the mold upward by a jigger separate from the mold and in which the finished product is ejected from the mold with its open top downward, substantially as set forth. 45
- 20 9. The combination of a frame carrying a number of jiggers, a mold supporting-frame independent of the jiggers and having on opposite sides a series of molds corresponding in number to the jiggers, a pallet carrying frame, feeding devices for the molds, and actuating mechanism, substantially as set forth. 50
- 25 10. The combination of a series of vertically sliding and rotating jiggers, a mold supporting frame having molds with ejecting devices 55
- 30
- on opposite sides of the frame, means for intermittently rotating said frame, a pallet carrying frame actuating devices for the jiggers, mold ejector and pallet carrying frame, feeding devices for automatically supplying a charge of clay to the empty molds and actuating devices for said feeding devices substantially as set forth. 60
11. In a feeding device for simultaneously conveying a number of successive stiff clay supplies to a series of molds a cutting device for dividing the clay into charges of the required bulk, means for positioning said charges apart from each other and adjacent to the molds into which they are to be delivered, and mechanism for discharging simultaneously all of the separate charges into their respective molds substantially as set forth. 65
12. In a feeding device for simultaneously conveying a number of successive clay supplies to different molds the combination of a clay supply forming device a traveling apron or conductor device and a series of limiting and pusher rods constructed for operation and having actuating devices substantially as set forth. 70

In testimony whereof I affix my signature in presence of two witnesses.

SMITH W. CLARK.
